UNITED STATES PATENT OFFICE.

ERNEST BENJAMIN FAHNESTOCK, OF BROOKLYN, NEW YORK.

SPRING TERMINAL CONNECTION.

1,240,186.

Specification of Letters Patent. Patented Sept. 18, 1917.

Application filed February 24, 1913. Serial No. 750,304.

To all whom it may concern:

Be it known that I, ERNEST B. FAHNESTOCK, a citizen of the United States, and a resident of the borough of Brooklyn, county 5 of Kings, city and State of New York, have invented certain new and useful Improvements in Spring Terminal Connections, of which the following is a specification, accompanied by drawings.

10 This invention relates to a spring terminal connection for use more especially in connecting a high tension cable to the post of a spark plug on the combustion engine of a motor vehicle, although the device may obviously be applied to any other uses for 15 which it is found suitable.

The high tension cables for electrically connecting the magneto to the spark plugs of an automobile engine are ordinarily provided with spring clips of some description, usually bare of insulation, so that there is danger from electric shock in connecting the clips to the posts of the spark plugs, since the clips are adapted to be grasped between 25 the fingers and pressed onto the posts.

The primary object of this invention is to secure a strong and efficient spring terminal connection which will not only firmly grip the post, but which may be manipulated 30 without danger of electric shock. My improved terminal connection comprises a body member, a spring member, and a third member adapted to coöperate with said body and spring members to clamp a conductor, 35 or it may comprise two spring members adapted to coöperate with each other to clamp a conductor, or it may comprise a body member and a spring member adapted to coöperate in such manner. In any case, 40 however constructed, non-conducting means are provided whereby said three members or said two members as the case may be, are forced into coöoperative position without danger of electric shock.

45 The invention is illustrated in the best forms known to me in the accompanying drawings, in which—

Figure 1 is a perspective view of one preferred form of the device open;

50 Fig. 2 is a side elevation of the device open;

Fig. 3 is a front end elevation of the device open;

55 Fig. 4 is a side elevation of the device clamped to the post of a spark plug;

Fig. 5 is a detail longitudinal sectional

elevation taken through the socket sleeve of the device with the spring terminal removed;

Fig. 6 is an end view of Fig. 5;

60 Figs. 7 and 8 are side elevations of modifications showing different forms of non-conducting operating means;

Fig. 9 is a side elevation partly in longitudinal section, of a modification showing a 65 different form of spring terminal;

Fig. 10 is a transverse section of Fig. 9 on the line 10—10 looking in the direction of the arrows, and

Fig. 11 is a side elevation partly in longitudinal section of a modification.

Referring to the drawings and at first more particularly to Figs. 1 to 6 inclusive, showing one of the preferred forms of the device, the spring terminal connection is 75 preferably formed of resilient metal, as for instance, a flat ribbon or strip of metal. In the preferred form of the invention, the spring terminal clip comprises a body member A, a spring member B and an intermediate member C which may be termed a resistant member. The clip is formed by bending the resilient metal, so as to form these three members A, B and C specified, and bring the third member C in between the 85 body A and the spring member B.

The spring member B is preferably slotted at D, so that the spring will not be too strong for easy manipulation although this slot may be omitted, if desired, and each member 90 A, B and C is preferably provided with an aperture a, b and c adapted to be brought into alignment when the body and spring members are forced into coöoperative position with the third member C, so that a conductor may be inserted through said apertures and then upon releasing the spring member the conductor is firmly gripped. In Fig. 4 the post E of a spark plug F is shown gripped by the spring terminal connection. 100

In order that the body and spring members may be forced into coöoperative position with the third member without danger of shock, non-conducting means are provided, in this instance, secured to both the body and 105 spring members. As shown, the spring member is provided with a block of insulation G forming a finger piece suitably molded thereon or otherwise secured thereto, and the body member A is forced into a sleeve H 110 of insulation, said sleeve being adapted at its free end to receive the end of an electric con-

ducting wire or cable J and means are also provided for electrically connecting said wire or cable J to the body member.

The sleeve H as shown is preferably provided with an inner plug or thimble K of brass or other conducting material internally screw threaded to receive the cable J. The brass plug K is preferably provided with shoulders d adapted to abut against 10 internal shoulders on the sleeve H and the plug. K is cut away at e, leaving a space between the brass plug and the sleeve of insulation H for the reception of the free end of the body member A. This free end 15 of the body member is preferably bent into trough shape form and thrust into the space between the brass plug or thimble K and the sleeve H. The inner ends of the sleeve H and plug K are beveled as shown to permit the finger piece G to have free play.

In manipulating the device, the insulating sleeve H is grasped between the fingers and the thumb is applied to the insulating finger-piece G, so that the body and spring 25 members may be forced into co-operative position with the third member without danger of shock. Upon releasing the pressure of the thumb on the finger-piece G the resiliency of the metal of the clip tends to 30 firmly clamp the device to a conductor at three points of contact. In the position shown in Fig. 4, the post or conductor E is gripped on one side by the body and spring members and on the opposite side by the 35 intermediate member C, so that the intermediate member pulls against the body member and the spring member, forming a lock.

Various non-conducting means may be 40 provided for manipulating the device without shock, and in Fig. 7, the insulating finger-piece G is omitted and a sliding sleeve O of insulation is provided upon the sleeve H. This longitudinally slidable sleeve O is 45 provided with an internally flared end P adapted to bear upon the spring member B of the spring terminal. The sleeve O is limited in its movement by any suitable means as a slot f through which passes a 50 pin g. The extent of the longitudinal movement of the sleeve O should be so determined and limited that by pushing the sleeve to its farthest extent in the direction of the spring terminal, the spring member of 55 the terminal will be compressed sufficiently to release the grip on the conductor, so that the conductor may be removed. After a conductor is inserted in the spring terminal, the sleeve is retracted to its farthest 60 extent, thereby permitting the members of the spring terminal to grip the conductor.

In Fig. 8, another modification is shown, in which a non-conducting piece or bar Q is 65 suitably hinged as at h to the sleeve H and bearing at its outer end j upon the spring

member B. By pressing upon the non-conducting piece Q, the spring terminal may be manipulated in an obvious manner.

In Figs. 9 and 10, another modification is shown in which the spring terminal comprises two spring members R and S and a body member T. The spring members are adapted to co-operate with each other to clamp a conductor. The spring member R as shown is provided with a hooked end k 70 having a slot o while the spring member S is provided with a hooked end p of reduced width adapted to enter the slot o, so that a conductor may be gripped between the two hooked ends. The two spring members R and S and the body member T may be formed in one piece, although they may be separate pieces and the body member T is preferably of trough shape form, so it 75 may be conveniently thrust into the insulating sleeve U and between said sleeve and the conducting plug or thimble V, as shown. A sliding sleeve W of insulating material is mounted for longitudinal movement upon the sleeve U and is provided with the internally flared end X adapted to bear upon the bowed portions of the spring members R and S, so that by moving the sleeve longitudinally, said members may be forced to 80 approach each other or permitted to recede from each other. A pin and slot connection f' and g' limits the movement of the sleeve W.

If desired, the member R shown in Fig. 9 may be formed of such stiff and strong 100 metal ribbon or other flat metal as to in effect form a body member practically incapable of being flexed, and in that case the member R, together with the member T would form the body member, while the 105 member S would form a spring member as before. Furthermore, the slot o may, of course, be in either member and the hoop p may be formed on either member, the construction in the drawing being merely an 110 illustration.

In Fig. 11 the body member R' is made straight and stiff and inserted in the sleeve U and provided with the hooked end k having the slot o as in Fig. 9, while the spring member S' is curved as in Fig. 9 and provided with the hooked end p' as in Fig. 9. The operating means may be like that shown in Fig. 8, comprising a non-conducting bar Q' hinged at h to the sleeve U.

I claim and desire to obtain by Letters Patent the following:

1. A spring terminal connection for electric wires formed of resilient metal and comprising opposed normally separated body and spring members, and a third member located intermediate the same, all of said members being adapted to receive a conductor and co-operate in clamping the conductor, said body member carrying a sleeve 125

- of nonconducting material and said spring member carrying a finger-piece of non-conducting material whereby said spring member may be forced toward the body member and into coöperative relationship with said third member and body member against the tension of the spring without danger of electric shock.
2. A spring terminal connection for electric wires formed of resilient metal and comprising opposed normally separated body and spring members, and a third member located intermediate the same and adapted to coöperate with said body and spring member to receive and clamp a conductor when said members are forced into coöperative relationship against the tension of the spring and then released, said body member carrying a protective sleeve of non-conducting material, said sleeve being adapted at its free end to receive the end of an electric conducting wire and means for electrically connecting said electric conducting wire to said body member.
3. A spring terminal connection for electric wires formed of resilient metal and comprising opposed normally separated body and spring members, and a third member located intermediate the same and adapted to coöperate with said body and spring member to receive and clamp a conductor when said members are forced into coöperative relationship against the tension of the spring and then released, said body member carrying a protective sleeve of non-conducting material, said sleeve being adapted at its free end to receive the end of an electric conducting wire, and non-conducting means whereby said spring member may be forced toward the body member and into coöperative relationship therewith against the tension of the spring, without danger of electric shock.
4. A spring terminal connection for electric wires formed of resilient metal and comprising two opposed normally separated spring members adapted when pressed together to coöperate with each other to clamp a conductor, a body member formed at a free end of said spring members, said body member carrying a protective sleeve of non-conducting material, said sleeve being adapted at its free end to receive the end of an electric conducting wire, and non-conducting means whereby the two spring members may be forced toward each other into coöperative relationship against the spring tension, without danger of electric shock.
5. A spring terminal connection for electric wires formed of resilient metal and comprising opposed normally separated body and spring members adapted to coöperate with each other to receive and clamp a conductor when the spring member is forced toward the body member and then released, said body member carrying a protective sleeve of non-conducting material, said sleeve being adapted at its free end to receive the end of an electric conducting wire, and non-conducting means whereby said spring member may be forced toward the body member and into coöperative relationship therewith against the tension of the spring, without danger of electric shock.
6. A spring terminal connection for electric wires formed of resilient metal and comprising opposed normally separated body and spring members, and a third resilient member forming a continuation of the spring member and located intermediate the body and spring members, the inner end of the intermediate member being adapted to bear upon the body member, all three members being provided with holes for the reception of an electric wire, said holes being brought into substantial alinement for inserting the wire by forcing the spring member toward the body member, and said wire being clamped and held in position by the reactive force of the spring member and intermediate resilient member.

In testimony whereof I have signed this specification in the presence of two subscribing witnesses.

ERNEST BENJAMIN FAHNESTOCK.
